UNITED STATES PATENT OFFICE.

ALBERT J. ISAACSEN, OF SALT LAKE CITY, UTAH.

TAG HOLDER.

Application filed March 13, 1922. Serial No. 543,379.

To all whom it may concern:

Be it known that I, ALBERT J. ISAACSEN, a citizen of the United States, and a resident of Salt Lake City, county of Salt Lake, and 6 State of Utah, have invented a certain new and useful Tag Holder, of which the following, together with the accompanying drawing, forms a full, clear, and exact specification, such as will enable others skilled in 10 the art to which it appertains to make and use the same.

This invention relates to a tag holder for displaying price tags, tickets, or other items, which it is desired to expose to public view, 15 the principal objects being,

First. To provide a light, neat and inconspicuous device for the purpose mentioned.

Second. A device into which the tags may be quickly placed and also be easily removed 20 therefrom, without distorting the tag.

Third. A holder which may be simply placed upon an object, or which may be readily attached to, or detached from, shelves or other structures.

25 Fourth. A holder which shall be designed with special reference to economical manufacture, so that it may be supplied to the user at a very reasonable cost.

In attaining these objects, I provide a 30 structure which may comprise a stem portion and a frame portion, the stem being adapted for suspending, or standing, in an approximately vertical position. A suitable support is provided at one end of the stem, while the other end thereof carries the said 35 frame portion. If so desired, the structure may be made of a single piece of wire. In general, beginning at the end of the stem which carries the frame, a transverse member may extend outwardly therefrom and at 40 a suitable distance from the stem, the wire may be formed into a U-shaped lug or hook from which a frame member, more or less inclined to the axis of the stem, may extend downwardly. At a suitable distance from the first U-shaped lug, the wire may be 45 formed into a second U-shaped lug or hook. Extending upwardly from the second U-shaped lug, there may be a second frame member, which may also be more or less inclined to the axis of the stem. At the upper 50 end of the second inclined frame member and suitably distant from the second lug, the wire may be formed into a third U-shaped lug or hook. A final frame member, transverse to the stem axis, may extend from the 55

third U-shaped lug to the stem at the point of origin of the first transverse member. In other words, the structure may be said to consist of a stem with a supporting connection at one end thereof, a frame member extending transversely outward from the stem at its other end in such a manner that the transverse member forms two arms or branches, with a hook-like lug at the outer 60 end of each arm; inclined converging frame members extending from the said two arms and a hook-like lug located at the intersection of the inclined frame members.

From what has been stated, it will readily 65 be seen that the structure in its preferred form, may have the shape of an isosceles triangle carried on a stem, the various lugs or hooks being located at the vertices of the triangle. As a rule, the stem and the frame 70 members may all lie in the same plane, while the lugs may be so formed, that a portion projecting from each lug will lie more or less in a second plane spaced apart from the first 75 plane.

80 The peculiar placing of the three lugs makes it possible for them to hold a tag or ticket, which may be round, square or have a number of other forms. Inasmuch as the third lug lies in a line perpendicular to the center line joining the other two lugs, a tag may be freely inserted in the holder by passing the tag through the two lugs in a direction substantially perpendicular to the said 85 center line, until the tag comes to rest with 90 an edge thereof against the third lug.

95 The features of my invention on which the protection of Letters Patent is desired, are collectively grouped in the claims by which this specification is concluded.

Referring to the drawing,

Fig. 1 illustrates a front elevation of my improved tag holder.

Fig. 2, a side elevation thereof.

Fig. 3, a view similar to Fig. 1, but showing a tag in position therein.

Fig. 4, a top plan view.

Fig. 5, a front elevation of a modified construction.

Fig. 6, a fragmentary side elevation of 105 the construction shown in Fig. 5.

Fig. 7, a front elevation of another modified construction, and

Fig. 8, a fragmentary view of a modified detail.

110 Referring to the drawing, 10 represents a stem which may occupy a more or less ver-

- tical position and have an eyelet 12 at its upper extremity. At its lower end, the stem 10 may carry the transverse member 14, at whose outer extremity is formed the 5 U shaped lug 15. The inclined member 16 may extend downwardly from the lug 15, and at its lower end the member 16 may have formed the U-shaped lug 17, from which the inclined member 18 may extend upwardly. 10 At its upper end, the inclined member 18 may have formed the U-shaped lug 19, and from here the member 20 may extend transversely and be joined to the stem 10 by means of the twisted fastening at 21. It 15 will be noticed that the stem 10 with all the concluding parts, may be formed of a single piece of wire having any suitable cross-section, usually round, the entire construction being designed for shaping by any 20 standard automatic wire forming machinery, such as is used in the quantity production of wire specialties. The holder may be suspended from a removable spring clip having the eyelets 24 and the body 25 and 25 the spring terminals 26 (Figs. 1 to 4). A clip of this form may be readily fastened to the edge of a shelf 27 and be held thereon, frictionally, by the spring tension of the clip. 30 If desired, the holder may be attached to the shelf 24 by means of the clip 31 illustrated in Figs. 5 and 6, where eyelet 12 of the holder is fastened in eyelet 30 of the clip. The eyelet 30 may be formed at one 35 end of clip 31, while another eyelet 32 may be formed at the other end thereof, and the clip may be fastened to the shelf by means of an ordinary wood screw 35 passing through the eyelet 32. 40 By referring to Fig. 7, it will be seen that instead of suspending the triangular frame in the manner already described, it may be supported by means of the standing stem 40, which may be attached to one side of the 45 triangular frame in any suitable manner, for instance by the twisted end 41. The stem 40 may have its lower end fastened in a base 42 made of any suitable material, though preferably of metal, the said base being 50 adapted for simply setting on a table, counter or other support 43. It will be noticed that in this case the frame 45 and the stem 40 are made of two separate pieces of wire. The stem 40, instead of having its lower 55 end fastened in the base 42, might be sharpened to a point, as illustrated at 46 (Fig. 8), in cases where it is desired to stick the holder into a comparatively soft mass, such as cheese, meat or similar substances. 60 The suspended type of this tag holder may also have the stem and frame made of two separate pieces of wire as indicated in Figs. 5 and 6, where 70 represents the stem and 60 the triangular frame. The trans- 65 verse frame members 61 and 62 may overlap

each other and the lower end of the stem 70 may be twisted around the overlapped ends as shown at 63.

In any of the constructions described, the method of holding the price tags is the same, 70 this being shown typically, in Figs. 3 and 5 where 50 represents a round tag, and the dotted lines a square tag. As the lugs 15, 17 and 19 offer three points of support, it will be readily understood that tags of many different shapes may be held with equal advantages. 75

While, for convenience, several specific structures are herein shown and described, it should be clearly understood that in these, 80 the detailed parts of this invention may, or may not, be shown in the preferred forms, and further, that the preferred forms may vary from time to time as the development of this invention and the arts with which it 85 is identified, progress.

To the skilled inquirer, therefore, that, which forms an essential and characteristic part of this invention, will be readily discernible from the claims, in which its spirit 90 is broadly generalized.

Having fully described my invention, what I claim is:

1. In a tag holder, the combination of a 95 stem portion having a frame member extending transversely therefrom, a hook-like lug formed at the outer end of the said frame member, an inclined frame member extending downwardly from the said lug, a second hook-like lug formed at the lower 100 end of the inclined member, a second inclined frame member extending upwardly from the said second lug, a third hook-like lug formed at the end of the second inclined frame member and a final frame 105 member extending from the said third lug, transversely to the said stem, and means for fastening the end of the said final member to the said stem.

2. In a tag holder, a stem portion, arms 110 extending laterally outward therefrom in directions opposed to each other, two tag-engaging upper lugs suitably disposed on the said arms, in position opposed to each other, frame members extending downwardly from said arms, and a tag engaging lower lug at the lower extremities of the frame members, the said three lugs being so shaped and so placed, relatively to each other, that a tag having a suitable shape, 115 shall pass between the two upper lugs without distortion, and shall come to rest on the said lower lug. 120

3. In a tag holder, a stem portion, a frame member attached to one end of the 125 said stem portion transversely therewith, the said transverse frame member comprising two branches extending from the stem portion in directions opposed to each other, the said two branches together forming the 130

base of an inverted triangle, a bent upper lug at each end of the said transverse frame member, inclined frame members extending downwardly and towards each other from the said lugs, and forming the two remaining sides of the said inverted triangle; a bent lower lug joining the lower ends of said inclined members; and fastening means at the other end of the said stem, the two 10 said upper lugs being so located relatively to each other that a tag of predetermined width may be passed between them without distortion, and the said lower lug being so located relatively to the two said upper lugs, that the said lower lug shall constitute a stop for the said tag when a predetermined point in the passage of the said tag through the said upper lugs shall have been reached.

4. In a tag holder, a frame portion more or less triangular in form, a U-shaped lug joining adjacent sides of the said frame at each vertex thereof, the said U-portions extending into a plane spaced apart from the plane of the said frame, a stem for supporting 25 the said frame, and means for supporting the said stem, the three said U-shaped lugs being so arranged that a plane tag of predetermined width may be passed freely through two of the said lugs, and so that 30 the said tag shall come to rest with its lower edge against the remaining one of the said three lugs, while the upper portion of the said tag remains in engagement with the two first-mentioned lugs. 35

In testimony whereof, I sign my name hereto.

ALBERT J. ISAACSEN.
